UNITED STATES PATENT OFFICE.

JAMES SHANNON, OF CANONBURY, LONDON, ENGLAND.

COOKING STOVE.

1,425,702.

Specification of Letters Patent. Patented Aug. 15, 1922.

Application filed February 16, 1922. Serial No. 537,070.

To all whom it may concern:

Be it known that I, JAMES SHANNON, a subject of the King of Great Britain and Ireland, residing at 37 Marquess Road, 5 Canonbury, in the administrative county of London, England, have invented certain new and useful Improvements in Cooking Stoves, of which the following is a specification.

10 This invention relates to cooking stoves, and has for its object to enable stoves adapted to burn coal and the like to be easily and readily converted into oil burning stoves.

15 With this and other objects in view the invention comprises the various novel features of construction, combination and arrangement of parts hereinafter fully described, illustrated in the accompanying drawings, and pointed out in the claims 20 hereto appended.

In the accompanying drawings in which similar parts are denoted by like characters of reference:—

25 Fig. 1 is a view in front elevation of a converted cooking stove fitted with a single oil vapour burner.

Fig. 2 is a view in transverse section on a line 2—2 of Fig. 1.

30 Figs. 3 and 4 are views in plan of an adjustable heat retaining plate or slab for the bottom of the grate, the former showing its adaptation to grates of a small size and the latter to grates of a larger size.

35 Fig. 5 is a view in side elevation of one of the elements of said plate or slab.

Figs. 6 and 7 are views in end and side elevation respectively of one of the filling-in or gap pieces for use with the adjustable plate or slab,

40 Figs. 8 and 9 are views in elevation and plan respectively of a detachable or hollow cone or bell-shaped grid for the heat retaining plate or slab.

45 Figs. 10 and 11 are views in plan and cross section respectively of an alternative form of heat retaining plate or slab, and

Fig. 12 is a plan of an elongated grid for use with the heat retaining plate or slab 50 shown in Figs. 10 and 11.

According to the present invention an oil vapour burner of the ordinary type comprising a burner head 1, a vapourizer, 1^a, a fuel nozzle 1^b, and an air induction or 55 mixing tube 1^c, is employed, said burner being of such a size and shape that it can

be located in that part of the range under the grate usually occupied by the ash pan. Cooperating with the burner is the usual fuel tank 2 which is provided with means 60 for creating pressure therein and is connected to the vapourizer by the pipe 3. On a metallic frame 4 adapted to fit in the grate in the place occupied by the fire bars is placed a heat retaining plate or slab 5 65 of fire brick or other suitable material which has a suitably shaped perforation 6, and on the upper side of said plate or slab above said perforation is formed or mounted a cone-shaped grid 8. Around and above 70 said grid are placed a number of the ordinary heat retaining balls or blocks 9. The perforation 6 in heat retaining plate or slab is so shaped and located as to substantially coincide with the shape and position of 75 the head of the burner.

In order to facilitate the fitting of the heat retaining plate or slab 5 in ranges having grates of different sizes said plate or slab may be made in two or more pieces, 80 the preferred construction being to make it in four sections of similar shape and size which when laid together will form a slab which will fill the bottom of a grate of minimum size as shown in Fig. 3 and 85 which can be spread to form a plate or slab which will fit a grate of a larger size by the use of four filling-in or gap pieces 7 adapted to occupy the spaces between the four sections of the plate or slab as shown 90 in Fig. 7.

In order to support the filling-in pieces in relation to the sections of the plate or slab they are made of a T-shape in cross section the vertical parts being adapted 95 to fit in the spaces between the adjacent sections of the plate or slab and the horizontal parts to rest in the tops of said sections.

When more than one oil burner or a 100 burner with a plurality of burner heads is employed the plate or slab 5 is provided with a plurality of perforations 6 as shown in Figs. 10 and 11 and when the plate or slab 5 is made in one piece the grid 8 is 105 preferably made integral with same but when said plate or slab is made in sections as shown in Figs. 3, 4, 10 and 11 said grid is made as a separate element as shown in Figs. 8, 9 and 12.

110 The front of the space below the grate of the stove is closed by a suitably shaped plate

10 for the purpose of enclosing the burner and protecting same from draughts. This plate can be conveniently suspended from the lower bar of the front of the grate and 5 is provided with a slot 10^a to permit of the passage of the fuel and induction pipes 3 and 1^c, and with one or more adjustable orifices 11 to permit of the adjustment of the amount of air passing to the burner head.

10 What I claim is:—

1. The combination with a cooking stove having a grate adapted to burn coal, of an oil vapour burner adapted to be placed in the space in the stove under the grate usually 15 occupied by the dust pan, a perforated heat retaining plate adapted to fit in the bottom of the grate, a hollow cone-shaped grid located above the opening in the heat retaining plate, and a plurality of heat retaining 20 balls located around and over said grid.

2. The combination with a cooking stove having a grate adapted to burn coal, of an oil vapour burner adapted to be placed in the space in the stove under the grate usually 25 occupied by the dust pan, a perforated heat retaining plate adapted to fit in the bottom of the grate, a hollow cone-shaped grid located above the opening in the heat retaining plate, and a plurality of heat retaining 30 balls located around and over said grid, and a plate adapted to close the space below the plate in which the vapour burner is located said plate being provided with a slot for the passage of the fuel and induction pipes.

3. The combination with a cooking stove having a grate adapted to burn coal, of an oil vapour burner of a size adapted to be placed in the space in the stove under the grate usually occupied by the dust pan, a 40 perforated heat retaining plate adapted to fit in the bottom of the grate, a hollow cone-shaped grid located above the opening in the heat retaining plate, a plurality of heat retaining balls located around and over said 45 grid, and a plate adapted to close the space below the grate in which the vapour burner is located said plate being provided with a slot for the passage of the fuel and induction pipes and with adjustable auxiliary air in- 50 lets.

4. In combination with a cooking stove having a grate adapted to burn coal, an oil vapour burner adapted to be placed in the space in the stove under the grate usually 55 occupied by the dust pan, a sectional per-

forated heat retaining plate adapted to fit in the bottom of the grate, a bell-shaped grid adapted to fit over the opening in the heat retaining plate, means for varying the size of said plate, and a plurality of heat retaining blocks located around and over said grid. 60

5. In combination with a cooking stove having a grate adapted to burn coal, an oil vapour burner adapted to be placed in the space in the stove under the grate usually 65 occupied by the dust pan, a sectional perforated heat retaining plate adapted to fit in the bottom of the grate, a hollow cone-shaped grid adapted to fit over the opening on the heat retaining plate, means for varying the size of said plate, a plurality of heat retaining balls located around and over said grid, and a plate adapted to close the space below the grate in which the oil burner 70 is located.

6. In combination with a cooking stove having a grate adapted to burn coal, an oil vapour burner adapted to be placed in the space in the stove under the grate usually occupied by the dust pan, a sectional perforated heat retaining plate adapted to fit in the bottom of the grate, a hollow cone-shaped grid adapted to fit over the opening in the heat retaining plate, filling-in pieces adapted to 80 coact with said sectional heat retaining plate, a plurality of heat retaining blocks located around and over said grid, and a plate adapted to close the space below the grate in which the oil burner is located. 85

7. For the conversion of a stove adapted 90 to be heated by a coal fire into a stove adapted to be heated by an oil burner, a plate of fire-brick or like heat retaining material for replacing the fire bars forming the bottom of the grate, said plate having a central perforation and a hollow cone-shaped grid located above said perforation. 95

8. For the conversion of a stove adapted to be heated by a coal fire into one adapted to be heated by an oil burner, an adjustable 100 perforated plate of fire-brick or like heat retaining material adapted to take the place of the fire-bars forming the bottom of the grate, said plate comprising four sections of equal size and shape and four filling-in pieces to 105 fit between said sections, and a hollow cone-shaped grid adapted to be placed on the top of said perforated plate above the opening therein.

JAMES SHANNON.
